(57) **CLAIM**

The ornamental design for a test and measurement instrument with stand and battery, as shown and described.

DESCRIPTION

FIG. 1 is a top, front, right, isometric view of a test and measurement instrument with stand and battery showing the new design in a first operating position;

FIG. 2 is a top, rear, left isometric view thereof;

FIG. 3 is a front elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear elevational view thereof;

FIG. 9 is a top, front, right, isometric view of a test and measurement instrument with stand and battery showing the new design a second operating position;

FIG. 10 is a top, rear, left isometric view thereof;

FIG. 11 is a front elevational view thereof;

FIG. 12 is a left side elevational view thereof;

FIG. 13 is a right side elevational view thereof;

FIG. 14 is a top plan view thereof;

FIG. 15 is a bottom plan view thereof; and,

FIG. 16 is a rear elevational view thereof.

The broken lines in the drawings depict environmental structure as well as unclaimed portions of the test and measurement instrument with stand and battery, neither of which form any part of the claimed design.
